Application January 4, 1936, Serial No. 57,548
In Germany April 15, 1935

4 Claims. (Cl. 179—171)

This invention relates to amplifiers comprising thermionic valves for low frequency oscillations such as those of audio frequency and has for its object to provide an improved circuit arrangement such that the amplification of powerful signals is greater than that of feeble signals. Such circuit arrangements are well known and are commonly referred to as volume expanders. They are particularly applicable to talking machine amplifiers. As is well known, with records, the ratio of the amplitudes of the sound track should always be, in the case of powerful and feeble points, substantially smaller than corresponds to the actual volume or intensity ratio. The use of an amplifier of this type will therefore ensure that reproduction approaches reality more closely. In wireless receiving sets such amplifiers can also often be used with advantage since the percentage variation of the modulation of the broadcasting waves is generally lower than the variation in intensity of the sound oscillations corresponding thereto.

It has previously been proposed to rectify part of the output energy and lead it back to the grid circuit of the first valve so that the amplification ratio of this valve is automatically controlled in accordance with the signal amplitude. In the well known arrangements the negative bias may readily decrease to an excessive extent on the occurrence of a powerful signal so that distortion ensues. This necessitates the use of devices which limit this effect.

According to the invention, the improved arrangement comprises an amplification ratio control valve which does not serve for the amplification of the low frequency oscillations and which receives its anode current through resistance included in the anode circuit of one of the amplifier valves. It comprises in addition, a rectifier that rectifies part of the output energy and supplies it to an impedance connected into the grid circuit of the first-mentioned valve, the arrangement being such that when the signal voltage increases the anode current of this valve decreases thereby decreasing the potential drop through the common resistance above referred to, whereby the mean anode voltage of the amplifier valve increases, causing the amplification to increase. The mutual conductance then becomes higher because of the decrease in the output or plate resistance of the valve.

In addition, according to the invention, the cathode of the first mentioned or control valve may be connected to a point on a resistance included in the cathode conductor of the amplifier

valve, whereby said valve may receive additional bias potential. Such a resistance may be a self bias resistor provided for automatically obtaining a negative bias for the amplifier. This resistance would bring about an increase of the negative bias in the case of an increase of the signal intensity because of the tendency to increase the plate current of the amplifier with increased plate voltage, so that the action above described would be partially neutralized. If in accordance with the invention, the cathode of the control tube or valve is connected to a proper point on this resistance, the grid bias may be made constant or may be made to decrease with increasing signal voltage.

In order that the invention may be clearly understood and readily carried into effect, one circuit arrangement in accordance therewith will now be described more fully by way of example, with reference to the accompanying drawing.

Referring to the drawing,

Figure 1 is a wiring diagram of an amplifier constructed and arranged in accordance with the invention,

Figure 2 illustrates the application of the invention to a plurality of different frequency channels, and

Figure 3 illustrates certain details of an amplifier similar to that of Figure 1 or 2.

Referring to Figure 1, 1 designates the first valve of an amplifier. The signals to be amplified are received at the terminals 6. The anode current is passed through a coupling resistance 4. The anode is in addition connected across a coupling condenser 13 to the diagrammatically illustrated amplifier 3 which may comprise in addition one or more amplifying stages and which supplies its output energy through an output transformer 12 to the load, for example, a loud-speaker. A further part of the output energy is supplied through a condenser 14 to a potentiometer 11 provided with a tap 16 which is connected through a condenser 18 to a rectifier anode 8.

An amplification ratio control valve 2 is connected in parallel with the valve 1, the anodes of the valves 1 and 2 being interconnected directly. The cathode of the valve 2 is connected to a point 7 on the resistance 5 which is included in the cathode lead of the valve 1. The resistance inserted in the cathode circuit is preferably capable of being varied by means of a contact 19. The resistance 5 serves for obtaining a negative bias for the grid of the valve 1.

The rectifier anode 8 is mounted in the valve 2

and the rectified current flows from the cathode of this valve across the resistance 9, one end of which is connected to the grid of the valve 2 and the other end of which is connected to the cathode 5 of the valve 2. The arrangement comprises in addition a balancing device or filter means 15 which may also serve for introducing a given time constant dependent, as is well known, upon the capacity of the filter means and the amount of 10 series resistance, indicated at 15a, which may be provided. In the present example, the filter is the usual series impedance, shunt capacitor type, of low pass filter interposed in the grid connection for valve 2 with the rectifier output 15 resistor 9.

The arrangement operates as follows:

Signals applied to the amplifier 1 through the input terminals are amplified thereby, and, after further amplification in the amplifier 3, are 20 applied to the receiver through the potentiometer connection as previously pointed out.

In case of a feeble or low amplitude signal applied to the terminals 6—6, the rectified component thereof, derived from the resistor 11 25 through the rectifier 8 will result in only a feeble current passing through the rectifier output resistance 9 so that the grid of the valve 2 is caused to be but slightly negative. The current then flowing through the valve 2 is great or relatively 30 high and the voltage at the anodes of the two valves is at a low value because of the potential drop set up by the current flow through the common anode resistor 4. In addition, the voltage drop across the resistance 5 is high because 35 the same anode current through resistor 4 also flows in resistor 5, and thus the negative bias of the grid of the valve 1 is also high. Under this condition the amplification of the valve 1 is low.

In the case of a powerful signal the rectified 40 component in the output resistor 9 is higher and the grid of the valve 2 becomes more highly negative. Therefore the anode current falls, for example, down to or toward zero and the voltage at the anode of valve 1 increases because of the 45 decreased potential drop in the resistor 9. The negative bias at the grid of the valve 1 decreases because of the decreased potential drop in the resistor 5 and decreased negative bias, and the amplification increases. In this manner, the contrast 50 between weak and strong signals is consequently intensified. Instead of being arranged in the valve 2, the rectifier may be arranged independently. In either case it applies to the grid of the control valve 1 a bias potential which 55 varies in response to change in the output current of the amplifier 3.

The contacts 7 and 16 are preferably slidable. The former permits of adjusting the variation of the negative bias of the grid of the valve 1 in the 60 case of a variation of the signal intensity. The latter permits of adjusting the operating effect of the control valve 2 and thus the intensity of the contrast between the amplification ratios at different signal strengths. The latter contact 65 may be coupled mechanically to the knob serving for the volume control which permits of ensuring that even in the case of adjustment to low strength of sound the contrast action is still maintained or is varied in accordance with a given law.

70 It is desirable to provide a filter 17 which serves to filter the high frequencies out of the energy derived from the amplifier 3 for the control of valve 2. This has the advantage that the contrast or expander action is not interfered with 75 by disturbances (in the case of wireless receipt)

and needle noise (in the case of talking machine reproduction). It may be possible to filter out or to weaken at the same time very low frequencies so that the contrast action is not interfered with by any particularly low sounds in a 5 given musical composition.

If, as is often the case, use is made of a low frequency amplifier arrangement subdivided into a plurality of parallel-connected amplifiers each of which serves to amplify a given frequency 10 band, the signals are preferably severed subsequent to the amplification by a valve 1. This is diagrammatically illustrated in Fig. 2 wherein V is the amplifying stage that comprises the valves 1 and 2, V₁ to V₄ are the subsequent amplifying 15 stages. The voltage required for the adjustment of the grid bias of the valve 2 is derived from one or more of the amplifiers, preferably from those that do not contain the very high or the very low frequencies, consequently, for example, 20 V₂ and V₃.

Figure 3 shows the manner in which the voltages are rectified and can be supplied to the grid of the valve 2. The valve comprises two rectifying anodes 8 and 8' which are connected to the cathode through resistances 9 and 9'. The arrangement comprises in addition two filters 15' and 15' for balancing the rectified signal voltage. The grid is connected to the output points of these filters.

What we claim is:

1. In a volume expander amplifier, the combination of an amplifier valve having a grid circuit and an anode output circuit, a control valve provided with an anode circuit connected in parallel with said amplifier anode circuit, said second anode circuit including a potential drop producing impedance in common with said first anode circuit, a rectifier, means providing a rectifier circuit connected to and energized from said amplifier output circuit and having a rectifier output impedance, said grid circuit being connected to said rectifier circuit output impedance to receive a biasing potential therefrom, and a circuit including a variable impedance device through which current is supplied to said rectifier circuit and a grid bias potential device common to said parallel connected anode circuits and to said amplifier grid circuit. 30

2. In a volume expander amplifier, the combination of an amplifier valve having a grid circuit and an anode output circuit, a control valve provided with an anode circuit connected in parallel with said amplifier anode circuit, said second anode circuit including a potential drop 45 producing impedance in common with said first anode circuit, a rectifier, means providing a rectifier circuit connected to and energized from said amplifier output circuit and having a rectifier output impedance, said grid circuit being connected to said rectifier circuit output impedance to receive a biasing potential therefrom, a circuit including a variable impedance device 50 through which current is supplied to said rectifier circuit, an impedance device common to said amplifier grid and said parallel connected anode circuits, and means for adjusting a portion of said impedance included in said grid circuit. 55

3. The combination of an amplifier valve including an anode, a cathode and a control grid, a rectifier having an anode, means providing a variable connection from said rectifier to said amplifier valve anode, said connection including a filter and a control valve connected to and energized from said rectifier anode, said control 70 75

valve including an anode connected directly to said amplifier anode, and a cathode connected to said amplifier cathode through a circuit including an adjustable impedance device through which anode current flows from said cathodes, said device being variably included in circuit with said control grid, and a circuit including a common anode resistor through which current is supplied jointly to said anodes.

4. In an audio frequency amplifier, the combination of an amplifier tube and a control tube, means providing a common anode resistor for said tubes and a common cathode resistor for

said tubes, said last named resistor being included in circuit with the grid of the amplifier tube to apply biasing potential thereto, means for adjusting said last named potential, means for deriving an amplified signal from said amplifier including a potentiometer device having a variable output connection, a rectifier device included in said connection, said rectifier having an output resistor, a control grid for said control tube connected with said output resistor, and a time delay filter in said last named connection. 5
